UNITED STATES PATENT OFFICE.

THEODOR HOLZHALB, OF BROOKLYN, NEW YORK, ASSIGNOR TO THE SEGAR STUDIOS INC., A CORPORATION OF NEW YORK.

DESIGN FOR A DECORATIVE GRILLE OR SIMILAR ARTICLE.

Application filed June 14, 1926. Serial No. 18,034. Term of patent 7 years.

To all whom it may concern:

Be it known that I, THEODOR HOLZHALB, a citizen of the United States, and a resident of the city of Brooklyn, county of Kings, and State of New York, have invented a new, original, and ornamental Design for a Decorative Grille or Similar Article, of which the following is a specification, reference being had to the accompanying drawing, forming a part thereof.

In these drawings:

Figure 1 is a side elevational view of the decorative grille or similar article showing my new design, and

I claim:

The ornamental design for a decorative grille or similar article, substantially as shown.

THEODOR HOLZHALB.
